UNITED STATES PATENT OFFICE

173,308

ELECTRIC IRON

Ivar Jepson and Robert O. Ernest, Oak Park, Ill.,
assignors to Sunbeam Corporation, Chicago, Ill.,
a corporation of Illinois

Application May 3, 1954, Serial No. 30,295

Term of patent 14 years

(Cl. D49—6)

To all whom it may concern:

Be it known that we, Ivar Jepson and Robert O. Ernest, both citizens of the United States and residents of Oak Park, in the county of Cook and State of Illinois, have invented a new, original, and ornamental Design for an Electric Iron, of which the following is a specification, reference being had to the accompanying drawings, forming a part hereof.

Fig. 1 is a perspective view of an electric iron embodying the new design of the present invention;

Fig. 2 is a somewhat enlarged side elevational view of the electric iron of Fig. 1;

Fig. 3 is a rear elevational view of the electric iron of Fig. 2;

Fig. 4 is a top plan view of the electric iron of Fig. 2; and

Fig. 5 is a front elevational view of the iron of Fig. 2.

We claim:

The ornamental design for an electric iron, substantially as shown.
